(57) **CLAIM**

The ornamental design for a compression sleeve, as shown and described.

DESCRIPTION

FIG. 1 is a right side perspective view of a compression sleeve of the instant invention, shown in a position of use. FIG. 2 is a front elevation view of the compression sleeve of FIG. 1.

FIG. 3 is a rear elevation view of the compression sleeve of FIG. 1.

FIG. 4 is a left side elevation view of the compression sleeve of FIG. 1.

FIG. 5 is a right side elevation view of the compression sleeve of FIG. 1.

FIG. 6 is a top plan view of the compression sleeve of FIG. 1; and,

FIG. 7 is a bottom plan view of the compression sleeve of FIG. 1.

The broken lines in FIG. 1 are for the purpose of illustrating environmental subject matter and form no part of the claim.

1 Claim, 4 Drawing Sheets
